DESK OR SIMILAR ARTICLE

Ralph B. Thompson, Chevy Chase, Md., assignor of two-fifths to John Henry Mahan, Washington, D. C.

Application June 4, 1953, Serial No. 25,324

Term of patent 14 years

(Cl. D33—7)

FIG. 2.

Fig. 1 is a perspective view of a desk embodying my new design, the opposite side being the same in appearance as the side shown and the back being plain; and

Fig. 2 is a front elevational view of the desk.

I claim:

The ornamental design for a desk or similar article, as shown and described.
